ABSTRACT

A new distinct variety of grapevine plant named 'ARD44' abundantly forms attractive crunchy seedless berries with a green skin coloration, medium density and medium clusters which display a Muscat flavor which is commonly ready for harvesting during July in San Joaquin Valley of Central California, U.S.A., and displays good eating qualities as a table grape having a firmness that renders the fruit well amenable for handling, shipping, and storage.

1 Drawing Sheet

1

Classification: The present invention relates to a new *Vitis vinifera* Grapevine.

Variety denomination: The new Grapevine plant has a varietal denomination 'ARD44'.

BACKGROUND OF THE INVENTION

A breeding program was initiated during the late 1990's near Bakersfield in San Joaquin Valley of Central California. In 2016, during this breeding program, a new variety of *Vitis vinifera* was created by deliberate cross breeding of two parent plants by emasculation of the pollen bearing organ of the female and introducing pollen from another male origin. The female parent of the new variety was 81E-39+5, which is an early and crispy seedless white table grape variety (non-patented in the United States). The male parent (i.e. the pollen parent) of the new variety was 8A-35+1, a very fertile and juicy seedless red variety (non-patented in the United States).

TABLE 1

'ARD44' compared with parents & closely related variety:

	'ARD44'	81E-39+5	8A-35+1	Thompson Seedless
Berry shape	Obtuse ovoid	Globose	Globose	Oblong
Berry attachment	Very good	Good	Very good	Medium
Flavor	Muscat	Natural sweet	Light Muscat	Sweet

The parentage of the new variety can be summarized as follows:

81E-39+5 X 8A-35+1

2

An artificial pollination was created, and the result was an embryo which possessed unique genetic qualities. The rudiments resulting from the above pollination were embryo rescued.

5 In 2017 the plant was transplanted to Bakersfield in San Joaquin Valley of Central California.

It was found that the new grapevine of the present invention possesses the following combination of characteristics:

- 10 (a) Forms attractive crunchy seedless berries with a green skin coloration; in medium density and medium clusters which display a Muscat flavor,
 (b) Commonly bears fruit during the month of July in the San Joaquin Valley of Central California, U.S.A., and
 (c) Bears fruit that is firm and is well amenable for storage, handling, and shipping.
 (d) Produces 44 bunches per vine, and an average of about 20 1 bunch per shoot, at a total of 79 lbs. fruit per vine.

The new variety during observation to date has displayed no visible disease, and has displayed an ability to well resist cold, drought, heat; but sensitive to direct exposure to sun and wind. The fruit of the new variety has been found to display excellent handling and shipping qualities combined with desirable dessert eating qualities.

25 The new variety of the present invention has been found to undergo asexual propagation beginning in 2018 near Bakersfield in the San Joaquin Valley of Central California, U.S.A. by bud grafting on mature Thompson seedless rootstock (non-patented in the United States). Such asexual propagation has been conducted thereafter in successive years to date and has shown that the characteristics of the new variety are strictly transmissible from one generation to another. Accordingly, the new variety undergoes asexual propagation in a true to type manner.

SUMMARY OF THE INVENTION

The new variety 'ARD44' is a green seedless table grape with high production, e.g., about 44 bunches per vine, and an average of about 1 bunch per shoot.

Asexual reproduction by micro propagation of the new variety as performed near Bakersfield, Calif., U.S.A., shows that the forgoing and other distinguishing characteristics come true to form and are established and transmitted through succeeding propagations.

BRIEF DESCRIPTION OF THE DRAWING

The accompanying photographic illustration shows typical six-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

FIG. 1 shows leaves, stems, tendrils, and grapes of 'ARD44'.

DETAILED BOTANICAL DESCRIPTION

The chart used in the identification of colors is The R.H.S. Colour Chart of The ROYAL HORTICULTURAL SOCIETY (3rd Edition). The description is based on the observation of plants growing on Thompson Seedless' rootstock outdoors near San Joaquin Valley of Central California, U.S.A.

TABLE 2

VINE CHARACTERISTICS:

Vigor	Vigorous upright shoots
Productive capacity	Bearing at natural, average capacity. Spur pruning.
Trunk	Strong and developed. Diameter is 2.9 inches at 5.7 inches above ground. Rough with a fibrous, shaggy exterior. Light brown coloring - greyed orange 177D

Date of bud burst in Bakersfield Calif.: February 22nd.

TABLE 3

YOUNG SHOOT CHARACTERISTICS:

Openness of tip	Fully open
Density of prostrate hairs on tip	Dense
Anthocyanin coloration of prostrate hairs on tip	None
Density of erect hairs on tip	Dense

TABLE 4

YOUNG LEAF CHARACTERISTICS:

Color of upper side of blade	Yellow green 152A
Color of lower side of blade	Yellow green 152B
Density of erect hairs between main veins on upper side of blade	Absent or very sparse
Density of erect hairs between main veins on lower side of blade	Absent or very sparse

TABLE 4-continued

YOUNG LEAF CHARACTERISTICS:

5	Density of prostrate hairs on main veins on upper side of blade	Sparse
	Density of prostrate hairs on main veins on lower side of blade	Sparse

TABLE 5

SHOOT CHARACTERISTICS:

10	Attitude (before tying)	Erect
15	Color of dorsal side of internodes	Yellow green 144A
	Color of ventral side of internodes	Yellow green 144B
	Color of dorsal side of nodes	Yellow green 144A
	Color of ventral side of nodes	Yellow green 144A
20	Density of erect hairs on internodes	Medium
	Density of prostrate hairs on internodes	Medium
	Length of tendrils	5.6 inches
	Diameter of tendrils	0.1 inches
	Color of tendrils	Yellow green 152B
25	Number of tendrils at bloom	3
	Positioning of first flowering and fruiting node	The first bunch is in the 3rd node
	Inflorescence number per flowering shoot	1

TABLE 6

FLOWER CHARACTERISTICS:

30	Reproductive organs	Fully developed stamens and fully developed gynoecium
35	Flower length	0.26 inches
	Flower diameter	0.2 inches
	Pistil length	0.13 inches
	Pistil color	Yellow green 144A
	Pollen Amount	Rich
	Pollen color	Yellow 7A
	Stamen color	Yellow green 144C
40	Stamen length	0.14 inches
	Number of stamen	5

First bloom in Bakersfield, Calif.: April 30th.

Date of full bloom in Bakersfield, Calif.: May 4th.

TABLE 7

MATURE LEAF CHARACTERISTICS:

45	Size of blade	5.7 x 5.3 inches
	Shape of blade	Wedge-shaped
	Base descriptors	Wedge-shaped
	Leaf margin	Serrate
	Leaf apex	Acute
	Blistering of upper side of blade	Absent or very sparse
	Depth of upper lateral sinuses	Shallow
	Number of lobes	Five
50	(Only varieties with lobed leaves)	Closed
	Arrangement of lobes of upper lateral sinuses	
	Arrangement of lobes of petiole sinus	Wide open
	Length of teeth	0.37 inches
55	60	Large
	Ratio length/width of teeth	Mixture of both sides straight and both sides convex
	Shape of teeth	Absent or very sparse
	Density of prostrate hairs between main veins on lower side of blade	Absent or very sparse
	Density of erect hairs on main veins on lower side of blade	Absent or very sparse

TABLE 7-continued

MATURE LEAF CHARACTERISTICS:	
Density of erect hairs between the main veins on upper side of blade	Strong (Red purple 58A)
Density of prostrate hairs on main veins on upper side of blade	Absent or very sparse
Length of petiole compared to length of middle vein	Equal
Top side color	Green 137B
Bottom side color	Yellow green 147B
Texture of upper side of blade	Smooth
Texture of lower side of blade	Rough
Vein color on upper blade	Yellow green 146C
Vein color on lower blade	Yellow green 145C
Venation pattern for upper blade	Netlike venation
Venation pattern for lower blade	Netlike venation
Petiole length	3.3 inches
Petiole diameter	0.1 inches
Petiole color	Yellow green 146D
Petiole texture	Smooth
Mature leaf anthocyanin coloration of main veins upper surface	Absent

Date of beginning of berry ripening in Bakersfield Calif.:
July 7th.

TABLE 8

BUNCH CHARACTERISTICS:	
Size (peduncle excluded)	Medium
Density of berries on bunch	Medium
Bunch length	9.8 inches
Bunch diameter	7.7 inches
Length of peduncle of primary bunch	3 inches
Diameter of peduncle of primary bunch	0.2 inches
Peduncle of primary bunch color	Yellow green 144C
Peduncle texture	Rough
Bunches per vine	44
Average bunch weight	1.8 lbs

TABLE 9

BERRY CHARACTERISTICS:	
Size	Medium
Length	0.9 inches
Weight	0.2 oz
Diameter	0.8 inches
Shape	Obtuse ovoid
Color of skin (without bloom)	Yellow green 150B
Flesh color	Yellow green 145D
Brix	24.1
Titratable acidity percentage	0.4%
Juice	4.24 pH
Ease of detachment from pedicel	Moderately easy
Thickness of skin	Thin
Anthocyanin coloration of flesh	None
Firmness of flesh	Moderately firm
Particular flavor	Muscat
Formation of seeds	None
Berries per bunch	135
Juiciness of Berry Flesh	Juicy

TABLE 10

PEDICEL CHARACTERISTICS:	
5	Length 0.34 inches
	Diameter 0.06 inches
	Color Yellow green 144C
	Pedicel texture Rough

TABLE 11

WOODY SHOOT CHARACTERISTICS:	
10	Woody shoot texture Smooth
	Woody shoot color Greyed orange 165A
	Woody shoot length 180 inches
	Diameter 0.4 inches
	Internode length 5.85 inches

Market use of observed plants: Fresh market.
20 Age and growing conditions: Six years growing under Y system in South Joaquin Valley (hot, dry summers).
Shipping characteristics: Fruit was in cold storage. Stored in poly bags inside polystyrene boxes with sulfur pads. After 60 Days: rachises were 50% green; 0% berry shattering; 25 no berry wrinkling or cracks were apparent.
DNA profile: To further the characterize the new variety DNA was extracted from plant samples and a DNA profile was obtained at California Seed & Plant Lab, California USA using base pairs for 10 standard microsatellite DNA markers. The data is presented hereafter.

TABLE 12

DNA profile for 'ARD44'		
	Microsatellite DNA Marker	Allele Sizes in Base Pairs
30	M 1	228 238
	M 2	239 249
	M 3	179 194
	M 4	210 212
	M 5	257 273
	M 6	135 149
	M 7	189 205
	M 8	255 257
	M 9	212 214
	M 10	247 247

45 The 'ARD44' variety has not been observed under all possible environmental conditions to date. Accordingly, it is possible that the phenotypic expression may vary somewhat with changes in light intensity and duration, cultural practices, and other environmental conditions.

50 Additional information relating to plant and fruit disease and pest resistance or susceptibility has not been observed to date. Specification of the plant hardiness zone and the heat/cold resistance has not been observed to date.

55 What is claimed is:

1. A new and distinct grapevine plant, botanically known as *Vitis vinifera*, identified as 'ARD44', substantially as shown and described herein.
